UNITED STATES PATENT OFFICE

2,627,098

REMOVABLE DEVICE FOR CLOTHING AND THE LIKE

Harold S. van Buren, Jr., Cambridge, Mass., assignor to United-Carr Fastener Corporation, Cambridge, Mass., a corporation of Massachusetts

Application September 2, 1948, Serial No. 47,431

9 Claims. (Cl. 24—219)

1

My invention aims to provide improvements in fastening devices for closures such as are used in connecting with articles of clothing and particularly for use on articles that require laundering and cleaning and where it is necessary or desirable to remove a part of the fastening device because it will not stand laundering or cleaning.

An object of my invention is to provide a snap fastener or button device where an ornamental part of the fastener or the button may be easily and quickly attached to or removed from the garment or the like.

Another object of the device is to provide for a device where that portion of the fastening means that cooperates with the removable part (and which remains attached to the garment) will be indestructible by ordinary cleaning and laundering processes.

It is also an object of my invention to provide a device which is useful in connection with quick and easy changing of the ornamental or button part of the device for style or color changing purposes.

Referring now to my invention as selected for illustration by the drawing forming a part hereof:

Fig. 1 is a front view of a portion of an application comprising a part of a closure and one embodiment of an improved fastening means for the closure;

Fig. 2 is a front view of that portion of the application showing the device that holds the removable part;

Fig. 3 is an enlarged section taken on the line 3—3 of Fig. 1;

Fig. 4 is a reduced section taken on the line 4—4 of Fig. 3;

Fig. 5 is a section similar to Fig. 4 but showing the sectional part of the removable part in removable position;

Fig. 6 is a section of a portion of the attaching part taken on the line 6—6 of Fig. 4.

Fig. 7 is a front face view of a snap fastener socket member that may be used with my invention;

Fig. 8 is a plan view of a prong attaching ring used to attach the socket;

Fig. 9 is an underside view of the removable member;

Fig. 10 is an underside view of a modified form of removable member; and

Fig. 11 is an enlarged section taken on the line 11—11 of Fig. 10.

Referring now to my invention as illustrated by the drawings I have shown an improved construction for use in connection with fasteners such as snap fasteners or buttons for closures of clothing and the like.

The same general construction may be used for buttons, ornaments or the like where it is

necessary to remove a button or an ornamental part of the fastener when the article of clothing or the like is to be dry cleansed or laundered. In the drawings I have confined the disclosure to a snap fastener of the laundryproof type with a removable ornamental part that may be metal, plastic, a combination of both or any other material that would be damaged if sent through dry cleansing or laundering processes. In my pending application Serial No. 47,432, filed September 2, 1948, I have disclosed and described removable buttons for clothing and the like closures suitable for use with the construction claimed herein for removably attaching a removable member to an attaching part.

The fastening means illustrated includes a stud installation comprising a carrying material 1, a snap fastener stud member 2 (Fig. 3), and a stud attaching member 3. A socket installation 10 to engage with the stud installation includes a carrying material 4, a socket member 5 and a socket attaching pronged ring 6. There is also included the removable construction forming my invention and it comprises a removable part 7, 15 and an attaching part 8 providing a hollow receptacle. This latter part may be assembled either with the stud or the socket but is herein shown as forming part of the stud installation.

The removable part 7 has a top portion and a shank 9 assembled as a unit. The shank 9 has a flange 10 at one end to which is assembled the top portion in the form of a cap 11 and at the other end of the shank I have provided oppositely directed tongues 12—12.

35 The attaching part 8, for receiving the removable part 7, comprises a shell 13 assembled with the stud attaching member 3 to form a hollow member with a noncircular aperture 14 for receiving the tongues 12—12 in one position as 40 shown in Fig. 5. When the removable part is rotated the tongues 12—12 pass under the shell 13 and snap by the bumps 15—15 and stop against the stops 16—16 as shown in Fig. 4. Thus the removable part is held against accidental displacement when in use and can be removed only by forceful rotation of the tongues 12—12 past the bumps 15—15.

45 My removable construction is simple, it permits the use of various ornaments, and the attaching part 8 is thin, strong to withstand hard usage as when laundered, and concealed by the removable part. As a strengthening means to prevent collapse of the shell 13 I have provided supporting tabs 17—17 between the shell and the stud attaching member 3.

55 One modified removable member is shown in Figs. 10 and 11 and is in the form of an ordinary sew-on button 18 having holes 19. Through the holes 19 I have assembled a metal construction 60 with legs 20—20 passing through two holes and

clamped against the underside of the button. Two other legs 21-21 pass through the other holes and have tongues 22-22 for removable engagement with the attaching part 8.

It should be understood that my attaching part 8 may be secured in position to the closure in any suitable manner and the button or ornament attached or detached easily and at will. My invention is simple in construction, durable, and fills a need for the use of fancy buttons or ornaments on clothing or the like. It eliminates the probability of the destruction of such ornaments and makes it easy for any person to remove and attach at any desirable time.

My invention is best defined by the following claims.

I claim:

1. A fastener member for securing a removable button part to articles of clothing and like supports comprising a tubular member having a shank portion for penetrating a supporting material and provided at one end with an outwardly flared peripheral flange, an attaching plate secured to and overlying said flange and provided with a central elongated aperture, a removable part provided with a shank extending from one face thereof and having opposed laterally extending ends forming an elongated locking element for insertion in the elongated aperture of said attaching plate and to be engaged under said attaching plate by relative rotation of said button, and stop means integral with said attaching plate and disposed between said attaching plate and flange for limiting rotative movement of said button and locking element in one direction.

2. A fastener member for securing a removable button part to articles of clothing and like supports comprising a tubular member having a shank portion for penetrating a supporting material and provided at one end with an outwardly flared peripheral flange, means engaging the opposite free end of said shank portion for securing said tubular member to a supporting material, an attaching plate secured to and overlying said flange and provided with a central elongated aperture, a removable part provided with a shank extending from one face thereof and having opposed laterally extending ends forming an elongated locking element for insertion in the elongated aperture of said attaching plate and to be engaged under said attaching plate by relative rotation of said button, and stop means integral with said attaching plate and disposed between said attaching plate and flange for limiting rotative movement of said button and locking element in one direction.

3. A fastener member for securing a removable button part to articles of clothing and like supports comprising a tubular member having a shank portion for penetrating a supporting material and provided at one end with an outwardly flared peripheral flange, a resilient attaching plate peripherally secured to and overlying said flange and provided with a central elongated aperture, said apertured attaching plate providing a supporting surface for removably receiving a button member provided with an elongated locking element having laterally extended ends, and stop means integral with said attaching plate and disposed between said attaching plate and flange for limiting rotative movement of the button and locking element in one direction.

4. A fastener member for securing a removable

button part and the like to a piece of supporting material comprising a tubular member having a shank portion for penetrating the supporting material and an outwardly flared dish-shaped flange at one end for engagement with a face of the supporting material, a resilient attaching plate secured to a peripheral portion of said flange and providing therebetween an axially restricted passage, said attaching plate being provided with an elongated opening, a removable part having a body portion and a generally T-shaped shank extending from one face thereof for insertion through the aperture of the attaching plate and for engagement with opposed faces of the flange and attaching plate upon rotation of the removable part, stop means integral with said attaching plate and disposed between said attaching plate and flange for limiting rotative movement of said button in one direction, and cam-shaped retaining means on said resilient attaching plate disposed in said axially restricted passage for resisting passage of said T-shaped shank rotatably in said passage between positions of alignment of said button shank and attaching plate aperture.

5. A fastener member as defined in claim 1 further characterized in that the attaching plate is provided with spacing means engaging said flange and disposed radially beyond said stop means for maintaining the flange and attaching plate in proper spaced relationship.

6. A fastener member as defined in claim 2 in which the means engaging the free end of the shank portion for securing the tubular member to a supporting material is a snap fastener member.

7. A fastener member as defined in claim 2 in which the means engaging the free end of the shank portion for securing the tubular member to a supporting material is a snap fastener stud member.

8. A fastener member as defined in claim 1 in which the removable part includes a disc member provided with opposed tongues extending angularly from said disc.

9. A fastener member as defined in claim 1 in which the removable part comprises a button member provided with a plurality of transverse apertures, a U-shaped member assembled with said button with its legs extending through certain of said apertures, the ends of said legs being outwardly turned to form said elongated locking element, and binding means extending through others of said button apertures for securing said U-shaped member to said button.
